UNITED STATES PATENT OFFICE.

—GEORGE W. ALLEN, OF BOSTON, MASSACHUSETTS, ASSIGNOR TO B. F. STURTEVANT COMPANY, OF BOSTON, MASSACHUSETTS, A CORPORATION OF MASSACHUSETTS.

PUMP FOR PNEUMATIC CLEANERS.

1,254,188.

Specification of Letters Patent. Patented Jan. 22, 1918.

Application filed December 1, 1918. Serial No. 803,938.

To all whom it may concern:

Be it known that I, GEORGE W. ALLEN, a citizen of the United States, residing at Hyde Park, Boston, in the county of Suffolk and State of Massachusetts, have invented certain new and useful Improvements in Pumps for Pneumatic Cleaners; and I do hereby declare the following to be a full, clear, and exact description of the invention, such as will enable others skilled in the art to which it appertains to make and use the same.

The present invention relates to pneumatic cleaners.

15 One object of the invention is to improve and reorganize the construction of the blower. Another object of the invention is to provide an improved outlet to adapt the cleaner for either suction or pressure work. 20 Still other objects of the present invention are to improve the construction of the cleaner in certain other details pointed out in the claims, the advantages of which will be apparent to those skilled in the art from 25 the following description.

With the above objects in view, the invention relates to the pneumatic cleaner herein-after described and particularly pointed out in the claims.

30 In the drawings which illustrate the preferred embodiment of the present invention, Figure 1 is a front elevation of the cleaner; Fig. 2 is a side elevation taken partly in section, the section through the front cover, 35 the dust drum, the inlet and discharge casings being a central vertical section, while the sections through the fans and the intermediate casings are taken substantially along the curved section lines 2—2 of Figs. 11 and 40 18, respectively; Fig. 3 is an enlarged detail view taken on a central vertical section and showing one of the fan casing bolts in position; Fig. 4 is a detail view of one of the catches for holding the dust bag to the front 45 cover; Fig. 5 is a front view of the inlet casing; Fig. 6 is a side elevation of the inlet casing taken partly in section along the line 6—6 of Fig. 5; Fig. 7 is a front view of one of the expansion plates; Fig. 8 is a section 50 taken along the line 8—8 of Fig. 7; Fig. 9 is a rear elevation of the discharge casing;

Fig. 10 is a section along the line 10—10 of Fig. 9; Fig. 11 is a front view of one of the intermediate casings; Fig. 12 is a section along the straight section line 12—12 of Fig. 11; Fig. 13 is a front view of one of the fans; Fig. 14 is a section taken along the straight section line 14—14 of Fig. 13; Fig. 15 is a detail view taken in rear elevation of the outlet; and Fig. 16 is a section taken along the line 16—16 of Fig. 15.

The pneumatic cleaner illustrated in the drawings is of the portable type with which a flexible suction hose and cleaning tool are employed. The cleaner comprises a dust collector 1, an air pump or blower 2 and an electric motor 3, all mounted together to form a self-contained cleaner supported on rubber-tired wheels 4 and provided with a handle 5 so that it may be conveniently rolled from place to place. The dust collector is a cloth bag 6 inclosed in a dust bag chamber 7. The dust bag chamber 7 is formed by the removable front cover 8, the cylindrical dust bag drum 9 and the inlet casing 10 of the blower. Back of the dust chamber is the air pump or blower of the multi-stage centrifugal fan type which consists of four fans or runners 11, 12, 13 and 14 inclosed in the fan casing 15. The fan casing 15 is built of five sections. These sections are the inlet casing section 10, three intermediate casings or sections 16, 17 and 18, and the discharge casing or section 19. Secured to the central portion of the rear face of the discharge casing is the motor casing 20.

The motor shaft 30 is supported by front and rear bearings 31 and 32 in the inlet casing and motor casing respectively. The fans are mounted on the motor shaft by means of elongated hubs 33 which are keyed to the shaft. The motor is balanced by means of balancing rings 34 and 35 which have a number of screw holes for the reception of set screws which are adjusted in and out to secure the proper balance.

The inlet, intermediate and discharge casings each have the outline of a short cylinder, the outer periphery of which is a smooth, unbroken, cylindrical surface so that when these casings are assembled to form the fan

2
casing, the fan casing has a smooth and unbroken cylindrical exterior which greatly conduces to the attractive appearance of the cleaner. The inlet, intermediate and discharge casings are all made of aluminum castings. When the castings are finished, the rear face of the inlet casing 10 is planed flat, the front and rear faces of each intermediate casing are planed flat and parallel and the front face of the discharge casing is planed flat. Because of this planing, the inlet, intermediate and discharge casings fit together, each casing forming a layer or lamina of the fan casing. The inlet, intermediate and discharge casings are rigidly held together in perfect alignment by means of five assembling bolts 40 which pass through bolt holes in the casings. The bolts are ground and the bolt holes are carefully reamed to secure accurate alignment of the casings. The front ends of the bolts are threaded in tapped portions of the bolt holes in the inlet casing. The bolts pass through bosses formed internally of the casings so that the smooth, cylindrical surface of the fan casing is not broken. The only place at which these assembling bolts are visible is where their heads 41 appear near the periphery of the rear wall of the discharge casing. The motor casing 20 is considerably smaller in diameter than the fan casing so that the exposed, annular rear wall of the discharge casing furnishes not only a suitable seat for the bolt heads 41, but also a space for the outlet 42 to be directed rearwardly. This construction in which the assembling bolts 40 extend inwardly from the discharge casting inside of the cylindrical outline of the fan casing and in which the discharge outlet is in the rear face of the cleaner, permits that portion of the cleaner body which contains the dust collector and fan to be a substantially perfect cylinder with a smooth and unbroken exterior which conduces to the distinctive and attractive appearance of the cleaner. The fan casing for the multi-stage fan built up as above described not only has an attractive appearance, but is a construction which, particularly when taken in connection with the expansion plates hereinafter described, is also very economical to manufacture.

The inlet casing 10 is illustrated in detail in Figs. 5 and 6. This inlet casing consists of an exterior thin annular plate or shell 50 of much shorter length than diameter and an interior annular web 51. The web 51 extends substantially radially inwardly from the shell 50 for substantially three-quarters of the distance to the center, leaving a central opening 52 through which passes the motor shaft and fan hub and which provides an annular intake passage 57 for the fan 11. As shown particularly in Fig. 6, the central portion 53 of this web,

which lies within the circle substantially described by the periphery of the fan 11, is flat. Beyond the periphery of the fan, the web is deflected or offset rearwardly to form an inclined annular shoulder 54. Beyond the shoulder 54, the web has a substantially flat portion 55 and at its periphery 56 where it merges with the shell 50 is again rearwardly deflected along a smooth curve, so that while the central flat portion 53 of the web 51 is located substantially midway of the length of the shell 50, the edge of the web merges with the shell 50 at its rear end. The flat central portion 53 of the web 51 forms with the partition plate 140 a fan 80 chamber, and the annular edge portions 53 and 56 form with the curved marginal portion of the partition plate a condensing educt for the fan 11.

On the front of the web 51 are five equally spaced, radially disposed, forwardly projecting wings 60 which support a plate 61 which furnishes the mounting for the shaft bearing 31. The wings 60 project sufficiently forward from the face of the web 51 so that ample air passages are left between the web 51 and plate 61 for the air to flow from the dust bag chamber 7 into the fan intake passage 57. In the wings 60 are tapped screw holes 62 for the reception of screws 63 by means of which a screen ring 64 is secured to the front of the inlet casing. The screen ring 64 furnishes a support for a forwardly convex wire screen 65, which serves to hold the end of the dust bag free from the front of the inlet casing. Formed on the inside of the shell 50, at the places where the wings 60 join the shell, are five equally spaced, longitudinally extending, substantially semi-cylindrical lugs or bosses 105 70. Each of these bosses is drilled and tapped to receive the reduced screw threaded end 71 of one of the assembling bolts 40. The rear mouth of the bolt hole is enlarged and reamed to receive the end of the ground stem of the bolt 40.

Back of the inlet casing 10 are the three intermediate casings 16, 17 and 18 which are all alike. The construction of the intermediate casings is shown in detail in Figs. 11 and 12 115 of the drawings. Each intermediate casing is made of a single aluminum casting and has the outline of a cylinder of much shorter length than diameter. Each intermediate casing consists of a thin, annular shell 80 120 having a smooth, cylindrical exterior surface and an interior annular web 81 which extends inwardly from the shell 80 about three-quarters of the distance to the center, leaving in the center of the web an opening 125 82. The motor shaft and the fan hub 83 extend through the opening 82 which is sufficiently larger than the hub to leave an annular air intake passage 87 for the fan. The central part 88 of the web 81, which lies 130

within the circle substantially described by the periphery of the fan 12, is substantially flat and is spaced about midway between the ends of the casing. Beyond the periphery 5 of the fan 12, the web is deflected to the rear to form an inclined annular shoulder 84. The annular portion 85, which lies between the shoulder 84 and the shell 80, is substantially flat except at its extreme outer edge 10 where it is deflected backwardly at 86 to smoothly merge with the shell 80 at its rear edge. The flat portion 83 of the web co-operates with one of the partition plates to form a circular chamber for the fan and 15 the portion 85 co-operates with the curved marginal portion of the partition plate to form a condensing educt for the fan. On the front face of the web 81 are formed ten equally spaced reversing vanes 90. The tops 20 or formed edges of the vanes 90 are flush with the forward end of the shell 80. In the unfinished casting from which the intermediate casing is made, there is a little surplus metal on the top of the vanes 90 and the 25 ends of the shell 80 which is removed when the ends of the casing are planed flat. This planing of the casing leaves the tops of the vanes 90 flat and flush with the finished front end of the shell 80. The vanes 90 at 30 their outer ends merge with the shell substantially tangentially to the shell and curve inwardly until at their inner ends which terminate at the opening 82 they are substantially radial. These vanes receive the air 35 which is discharged from the condensing educt more or less tangentially from the fan, gradually check its tangential movement and discharge it through the central opening into the next fan. Formed on the inside of 40 the shell 80 at the bases of alternate vanes are five equally spaced, longitudinally extending, substantially semi-circular lugs or bosses 91, which are drilled and reamed to receive the ground shafts of the bolts 40. It 45 is to be noted that these bosses 91 formed as they are at the bases of the vanes 90 require very little extra metal and moreover do not interfere or obstruct the passage of the air. Each of the vanes 90 is drilled and 50 tapped to provide screw holes 92 for the reception of the screws by means of which a partition plate is rigidly secured to the intermediate casing.

Back of the intermediate casings is the 55 discharge casing 19, which is shown in detail in Figs. 9 and 10. This discharge casting consists of a thin cylindrical annular shell 100 and a web 101 which forms the rear wall of the fan casing. The web extends inwardly from the shell 100 substantially flush with the rear end of the shell to form the flat annular exterior face 102 of the fan casing which lies radially outside of the forward end of the motor casing 60 20. The center of the web 101 is dished or offset forwardly to form a shallow circular cavity 103 which forms the forward end of the motor containing chamber. The web has a central opening 104 just large enough for the passage of the motor shaft 30. An annular flange 105 projects rearwardly around the mouth of the recess 103 and is shouldered and finished to form a seat for the forward end of the motor casing 20 which is rigidly bolted to the discharge casing. Through the upper part of the annular flat portion 102 of the web are three bolt holes 106 for the reception of the bolts 107 which secure the base of the cleaner handle 5 to the casing. Projecting from the forward face of the web 101 are bosses or lugs 108 which are drilled and tapped to receive screws for holding one of the partition plates. In the unfinished casting from which the discharge casing is made, some surplus metal is left on the forward ends of the shell 100 and the bosses 108. This surplus metal is removed from the front face of the casing and planed flat so that the ends of the bosses are flat and flush with the edge of the shell 100. Formed on the inside of the shell 100 are five equally spaced substantially cylindrical bosses 109 which are drilled and reamed to receive the bolts 40. Two downwardly extending legs 110 which are cast integral with the discharge casing furnish a support for the rear axle 111 of the cleaner.

Cut through the back of the discharge casing is an elongated arcuate slot 120 through which the air is discharged. Fitted in this slot is a split nipple 121 which is shown in detail in Figs. 15 and 16. This split nipple consists of a stationary and a movable part 122 and 123 respectively. The stationary part and movable part have rearwardly extending semi-circular flanges 124 and 125 respectively, which, when the two parts of the nipple are moved together, form a short tapered collar over which a coupling may be fitted so that the air discharged from the fan may be led through a hose for cleaning where air under pressure is desired. The fixed part of the nipple 122 has a flat plate or flange 126 which fits inside of and is secured to the casing 19 by means of screws 127. The movable part of the nipple 123 has a flat arcuate-shaped plate 128 which fits against the inside of the casing 19 and is mounted to slide between guide flanges 129. The plate 128 is held snugly against the inside of the rear wall of the casing by means of a spring 130, which bears against the flat contact plate riveted on the partition plate 143. When the two halves of the nipple are 125 drawn together to receive a hose coupling, the plate 128 closes all of the slot 120 external to the nipple opening. When the cleaner is used for suction work, it is desirable to have a large discharge opening to prevent 130

back pressure on the fans and under such circumstances the two parts of the nipple are separated, the movable part being moved to the opposite end of the slot from the fixed part so that practically the entire area of the slot 120 is available for the exhaust.

Secured to the fronts of each of the three intermediate casings 16, 17 and 18 and the discharge casing 19 are the four partition plates 140, 141, 142 and 143. These partition plates are shown in detail in Figs. 7 and 8. Each partition plate consists of a single piece of sheet iron having through its center an opening 144 just large enough to fit loosely around the hub 33 of a fan, and having a number of small screw holes 145 through which pass the screws to secure the partition plate to an intermediate or the discharge casing. The central portion 146 of the partition plate, for a diameter substantially equal to that of the fans, is flat. Beyond the periphery of the fan, the partition plate is spun or deflected forwardly to form an inclined annular shoulder 147 which projects forwardly to the radial plane which passes through the rear edge of the fan. Beyond the shoulder 147, the edge of the plate is spun or deflected rearwardly to form the rear wall 148 of the condensing educt of the fan. The extreme edge of the partition plate is bent to form a short rearwardly extending lip 149. These partition plates are very cheap to make and when combined with the cast sections of the fan casing make a composite fan casing which is cheap to manufacture and very easily assembled. The fan casing is thus built up entirely of the castings which form the cylindrical inlet, intermediate and discharge sections and sheet metal partition plates. The fan chambers, the diffusers and the passages through which the air is led from one fan to another are all formed between the fan casing castings and the partition plates, so that it is unnecessary to employ cored castings. The economy of building up the entire fan casing of uncored castings and sheet metal plates is obvious.

The four fans or runners 11, 12, 13 and 14 are all alike and are illustrated in detail in Figs. 13 and 14. Each fan consists of the fairly long hub 33 which is splined to the motor shaft and a cored substantially flat thin circular fan portion 150. The circular fan portion 150 comprises a circular rear plate 151 which extends outward from the rear of the hub and is very slightly inclined forwardly, a flat annular front plate 152 and a number of curved blades 153 extending outwardly from the hub between the rear and front plates 151 and 152. The whole fan is made of a single aluminum casting, the air passages 154 between the blades 153 being cored in the casting. The inner edge of the front plate 152 is spaced

away from the hub to form an annular inlet 155 which is of substantially the same size as the annular intake passages 57 and 87 through the webs of the casings. A shallow flange 156 projects forwardly from the fan 70 just inside the inner edge of the casing web to prevent air leakage between the fan and web. The air which enters the fan longitudinally through the inlet 155 is discharged from the periphery of the fan in a direction 75 partially tangential and partially radial. The flow of air through the fans is indicated by the arrows in Fig. 2. For the sake of more clearly and diagrammatically illustrating the flow of air, the section through 80 the fans shown in Fig. 2 is taken so as not to intersect any of the fan blades, such a section being indicated by the curved section line 2-2 in Fig. 13, and the section through the intermediate casings shown in 85 Fig. 2 is taken so as not to intersect any of the vanes 90, such a section being indicated by the curved section line 2-2 in Fig. 11.

For the sake of explaining the passage of the air through the fans, the passage of the 90 air through the fan 12 and from the fan 12 to the fan 13 will be considered. The air enters the inlet opening 155 in the fan 12 flowing in a direction substantially axially of the fan. The air is thrown outwardly by 95 the centrifugal action of the fan blades 153. The substantially flat front and rear walls 150 and 151 of the fan converge slightly toward the periphery of the fan, so that the air passages 154 in the fan have a substantially uniform cross section. The air, as it is discharged from the periphery of the fan, is flowing in a direction partially radial and partially tangential to the fan. The air thus discharged from the fan passes into the annular throat 160 (see Fig. 2) between the partition plate 141 and the annular shoulder 84 on the web 81 of the intermediate casing 16. The air, after passing through the throat 160, enters the diffuser 161. The 110 diffuser 161 is formed between the relatively diverging, annular portions 85 and 148 of the web 81 and the partition plate 141. The function of the diffuser 161 is to transform a part of the kinetic or velocity energy of 115 the air, as it leaves the fan, into static pressure. This transformation of the kinetic energy of the air into static pressure causes a condensation or diminution in the volume of the air. The increase in cross section of 120 the diffuser 161 is such that the velocity-pressure transformation takes place without shock and this contributes greatly to the efficiency of the fan. It is to be noted that the diffuser 161 forms an annular passage 125 surrounding the fan and devoid of any vanes or obstructions. It is found that with the construction of the diffuser as herein illustrated and described the noise incident to the blowing of the air is reduced to a mini- 130

num. This is of particular importance in a portable cleaner in which of necessity the blower must be present in the room or apartment being cleaned. The air, as it leaves the diffuser 161, is deflected rearwardly between the curved portion 86 of the web 81 and the lip 149 of the partition plate 141. The curved portion 86 of the web merges smoothly with the flat wall 85 of the diffuser 10 and with the inner wall of the shell 80 of the intermediate casing 17, so that the air is deflected without shock and is discharged flowing rearwardly and tangentially into the space between the front of the web of the 15 intermediate casing 17 and the back of the partition plate 141. The space between the web of the intermediate casing 17 and the partition plate 141 is divided into a number of passages 162 by means of the vanes 90. 20 These passages 162, as shown in Fig. 11, receive the air which is flowing more or less tangentially and gradually lead it inward along a smooth curved path and discharge it flowing substantially radially inward at the 25 mouth of the intake passage of the next fan 13. The diffuser 161 formed between the inlet section 10 and the partition plate 141 is identical in shape with that formed between the intermediate casings and their 30 partition plates. The air discharged from the last fan 14 is directed into the annular exhaust chamber formed inside the discharge casing 19 from whence it is discharged through the discharge opening 42. 35 The dust bag drum 9 is made of sheet iron bent into cylindrical shape. This drum is secured at its rear end inside of the inlet casing 10 by means of a number of rivets 170. The front end of the drum is similarly 40 riveted inside of a drum collar 171. The lower edge of the drum collar is provided with a seat 172 through which passes a bolt 173 on which is swiveled the single front wheel of the cleaner. The annular front 45 face of the drum collar 171 is finished perfectly plane and flat. The front of the dust bag drum is closed by the front cover 8, the rear face of which is finished around the margin to fit (with the interposition of a 50 rubber gasket 200) against the front face of the drum collar 171. The collar is removably held in place by means of four bolts 174, 175, 176 and 177, which are provided with thumb nuts 178. The two lower bolts 55 174 and 175 are rigidly secured to the drum collar 171, while the upper bolts 176 and 177 are swing bolts hinged to the drum collar 171 so that they may be lifted. The edge of the front cover 8 has four ears which are 60 slotted to receive the bolts 174, 175, 176 and 177. When the cover is put in place, the swing bolts 176 and 177 are lifted and the cover is placed on the fixed bolts 174 and 175 which support its weight. Then the swing 65 bolts 176 and 177 are dropped into their slots,

and the thumb nuts are tightened to clamp the cover. With this arrangement of bolts for securing the cover in place, the presence of any guide flanges on the cover is unnecessary and the flat engaging surfaces of the 70 drum ring and the cover need be simply machined flat.

The suction hose, which is used with the cleaner, is provided with a connection which fits within and is frictionally held in the inlet 180 in the front cover. The inlet 180 is provided with a cover 181 hinged at 182 above the inlet. When the suction hose is disconnected, the cover 181 falls by gravity and closes the inlet. The closure of the 75 inlet prevents the escape of dirt from the dust bag and particularly when the front cover is removed and lifted by its handle 183. The front cover also prevents overload of the blower and diminishes the noise in 80 case the suction hose is taken off while the blower is running. Without this front cover, if the suction hose should be removed, a large volume of air would be freely admitted to the dust bag, not only overloading 85 the motor, but also causing a loud whistling noise as it is drawn into the open inlet. As the cover 181 automatically drops when the hose is removed this is automatically prevented. When the cleaner is to be used for 90 pressure work, the front cover is taken off and turned upside down, which is permitted because the slotted ears at the top and bottom of the front cover are alike. In its inverted position, the inlet cover 181 hangs 95 open and freely admits air to the blower.

The mouth of the dust bag 6 is secured by means of a binding wire 190 to a mouth ring 191 which is of substantially L-shaped cross section as shown in Fig. 4. This ring carries 100 a number of spring catches or clips indicated generally by reference numeral 192. Each clip consists of an arm 193 securing it to the mouth ring 191 to which is hinged at 105 194 a hook 195. The hook 195 is normally 110 spring-pressed toward the mouth ring by means of the spring 196 against the tension of which it may be moved by a push button 197. The inside of the cover 8 is provided with an annular flange 198, the end of which 115 has an inwardly directed beveled rib 199 for the hooks 195 to engage. The flat annular gasket 200 affords a dust tight packing between the front cover and mouth ring and also between the front cover and dust drum 120 collar. When the dust bag is to be emptied, the hose connection is removed from the inlet 180, the thumb nuts 178 are loosened and the front cover 8 and attached dust bag 6 are lifted out by means of the handle 183 125 and carried out of the room for emptying. To remove the dust bag 6 from the cover 8 to empty it, the push buttons 197 are pressed in, releasing the catches 192 so that the dust bag may be removed. When the dust bag 130

is to be put back, it is simply pressed into place, the hooks 195 sliding over and catching behind the beveled lip 199.

While the preferred embodiment of the present invention has been illustrated and described, it is to be understood that the present invention is not limited to its preferred embodiment, but may be embodied in other structures within the scope of the invention as set forth in the following claims:—

1. The combination of a blower, a discharge casing for the blower having an elongated opening therein, a split nipple comprising two relatively movable parts which may be separated to uncover substantially the entire opening, one of said parts being provided with a closure plate for closing a portion of said opening when the two halves 20 of the nipple are together, substantially as described.

2. The combination of a blower, a discharge casing for the blower having an elongated opening therein, a split nipple comprising a fixed and a movable half, each half having a semi-circular collar forming a half of the nipple, and the movable half having a flat closure plate fitted to slide over the opening so that substantially the entire opening may be uncovered when the two halves of the nipple are separated and the opening may be closed except for the nipple opening when the two halves are together, substantially as described.

3. The combination of a blower, a discharge casing for the blower provided with an outlet having provision for receiving a pressure pipe connection and comprising two relatively movable parts which may be separated to enlarge the outlet opening when the pressure pipe connection is removed, substantially as described.

4. The combination of a blower, a discharge casing for the blower having an elongated opening therein and parallel guide flanges on the inside of the casing at the sides of the elongated opening, a split nipple comprising two relatively movable parts which may be separated to uncover substantially the entire opening, one of said parts being provided with a closure plate fitting against the inside of the casing between the guiding ribs and a means for holding the plate against the inside of the casing and permitting it to slide between the guide flanges, substantially as described.

5. The combination of a plurality of fans mounted on a common driving shaft, a fan casing comprising a cylindrical inlet casing having a plane rear end face, a cylindrical discharge casing having a plane front end face, and one or more intermediate casings, each intermediate casing comprising an externally smooth cylindrical shell having 65 plane parallel end faces and a central web

within said shell provided with a central opening and having vanes extending inwardly from the shell toward the central opening and provided with longitudinally extending bolt holes where the vanes join the shell, said bolt holes being aligned with similarly situated bolt holes in the other casings, and bolts passed through the bolt holes within the shells for holding the casings rigidly assembled, substantially as described. 75

6. The combination of a centrifugal fan and a fan casing, including a section consisting of a cylindrical shell and a central web extending inwardly from the shell and having a central opening therethrough, a second and adjacent section fitting against the first section, and a sheet metal partition plate secured to the second section between it and the first section, the web and partition plate being spaced apart at their central portions to form a fan chamber and having relatively divergent annular surfaces beyond the periphery of the fan to form a diffuser therefor, substantially as described. 80

7. The combination of a plurality of centrifugal fans mounted on a common driving shaft and a fan casing including a plurality of sections, one section consisting of a substantially cylindrical outer shell and a central web extending inwardly from the outer shell and having a central opening therethrough forming an intake for one of the fans, the rear face of said web having its central portion dished to receive a fan, a second and adjacent section consisting of a substantially cylindrical outer shell and a central web extending inwardly from the outer shell and having a central opening therethrough forming an intake for another fan, the front face of said web being provided with a plurality of inwardly extending vanes the top edges of which are flush with one edge of the shell, and a partition plate secured to the tops of the vanes and cooperating with them to form a plurality of inwardly directed air passages and cooperating with the dished central portion of the web of the adjacent section to form a circular fan chamber, substantially as described. 95

8. The combination of a plurality of centrifugal fans mounted on a common driving shaft and a fan casing including a plurality of sections, one section consisting of a substantially cylindrical outer shell and a central web extending inwardly from the outer shell and having a central opening therethrough forming an intake for one of the fans, the rear face of said web having its central portion dished, a second and adjacent section consisting of a substantially cylindrical outer shell and a central web extending inwardly from the outer shell and having a central opening therethrough forming an intake for another fan, the front 110 face of said web being provided with a plurality of inwardly extending vanes the top edges of which are flush with one edge of the shell, and a partition plate secured to the tops of the vanes and cooperating with them to form a plurality of inwardly directed air passages and cooperating with the dished central portion of the web of the adjacent section to form a circular fan chamber, substantially as described. 115

- race of said web being provided with a plurality of inwardly extending vanes, and a partition plate secured to the tops of the vanes and coöperating with them to form a plurality of inwardly directed air passages and coöperating with the dished central portion of the web of the adjacent section to form a circular fan chamber, the partition plate and the rear wall of the said dished web being relatively divergent beyond the periphery of the fan to form a diffuser, said plate being of less diameter than the internal diameter of the outer shells to afford an opening around the edge of the plate from the diffuser to the inwardly directed air passages, substantially as described.
9. The combination of a plurality of centrifugal fans and a fan casing consisting of a plurality of circular fan chambers having axial intakes, annular diffusers around the periphery of the fan chambers having relatively divergent walls, one of said diffuser walls extending radially beyond the other wall and terminating in a curved portion to form a longitudinally directed discharge for the diffuser into the next adjacent fan chamber, said casing having air passages for receiving the air from each diffuser and leading it to the axial intake of the next fan, substantially as described.
10. An intermediate section for a fan-casing consisting of a substantially cylindrical outer shell and a central web extending inwardly from the shell and having a central opening therethrough, said web being provided upon one side with a number of inwardly extending air directing vanes, the other side of the web having its central portion dished so as to receive the fan between it and the plane of the adjacent end of the shell and having its marginal portion where it joins the shell curved to merge with the shell, substantially as described.
11. The combination of a plurality of centrifugal fans mounted on a common driving shaft, a fan casing comprising an inlet casing, a discharge casing and one or more intermediate casings, each of said casings comprising a substantially cylindrical outer shell having end faces fitting corresponding faces on the adjacent section, some of said sections being provided with central webs disposed substantially midway between the ends thereof and extending inwardly from the outer cylindrical shells, and a plurality of dish-shaped sheet metal partition plates of less diameter than the diameter of the sections secured between said webs and coöperating therewith to form fan chambers and air passages for leading the air from fan to fan, substantially as described.
12. A portable pneumatic cleaner having a horizontal body, a cover for closing the front of the body and having an inlet for dust laden air, a hinged door or flap on the outside of the cover, means for removably securing the cover in place so as to cause the door to be closed by gravity in one position of the cover and to be held open by gravity in another position of the cover, substantially as described.
13. The combination in a portable pneumatic cleaner of a cylindrical horizontal body having an open front end, a circular cover closing said open end, a plurality of fixed bolts extending forwardly from the body and a plurality of swing bolts located vertically above the fixed bolts, ears on the edge of the front cover having downwardly and upwardly opening slots for the reception of the fixed and the swing bolts respectively, said ears permitting the front cover to be positioned either right side up or upside down, substantially as described.
14. The combination of a plurality of centrifugal fans mounted on a common driving shaft and a fan casing including a section having a substantially cylindrical outer shell and an interior annular web having a central opening, and a fan-receiving portion disposed substantially midway between the ends of the shell and an annular flat portion connected with the fan-receiving portion by a rearwardly inclined shoulder, the flat annular portion being deflected rearwardly at its outer edge to smoothly merge with the shell, a second and adjacent section fitting against the first section and having a substantially cylindrical outer shell and an interior annular web provided with a central opening, and a partition plate of less diameter than the internal diameter of said shells mounted between the sections and coöperating with the web of the first section to form a delivery chamber located substantially in the plane of rotation of the fan, substantially as described.
15. The combination of a plurality of centrifugal fans mounted on a common driving shaft and a fan casing including a section having a substantially cylindrical outer shell and an interior annular web having a central opening, and a fan-receiving portion disposed substantially midway between the ends of the shell and an annular flat portion connected with the fan-receiving portion by a rearwardly inclined shoulder, the flat annular portion being deflected rearwardly at its outer edge to smoothly merge with the shell, a second and adjacent section fitting against the first section and having a substantially cylindrical outer shell and an interior annular web provided with a central opening, and a partition plate having an annular shoulder projecting forwardly, and a marginal portion deflected rearwardly, the partition plate being mounted between the sections and coöperating with the web of

the first section to form an annular diffusing chamber for the fan, substantially as described.

16. The combination of a plurality of fans mounted on a common driving shaft, and a fan casing including a plurality of sections some of which have central webs and a plurality of sheet metal partition

plates located between the sections and co-operating with the central webs to form fan 10 chambers and air passages.
